RUNNING BOARD

Charles S. Johnston, Chicago, Ill.

Application November 16, 1939, Serial No. 304,865

4 Claims. (Cl. 105—457)

My invention relates to running boards and the like for railway cars and more particularly to metal running boards of the type having a plurality of substantially upright longitudinally extending members which are connected by a plurality of transverse bars, the upper edges of the members and bars affording a tread surface.

The primary object of the invention is to provide an extremely rigid running board of the character indicated wherein the component parts thereof are firmly interlocked and may be easily and quickly assembled by unskilled labor.

Features of the invention, residing in advantageous forms, combinations and relations of parts, will hereinafter appear and be pointed out in the claims.

In the drawings:

Figure 1 is a plan view of a portion of the roof of a railway car illustrating my invention.

Figure 2 is an enlarged sectional view taken on line 2—2 of Figure 1.

Figure 3 is a plan view of the construction illustrated in Figure 2.

Figure 4 is a sectional view taken on line 4—4 of Figure 2.

Figure 5 is an enlarged sectional view taken on line 5—5 of Figure 1.

Figure 6 is an enlarged side elevational view of a portion of the running board.

For purposes of illustration, the invention is shown as applied to a refrigerator car, but it will be appreciated that it is equally applicable to cars of other types. The roof of the refrigerator car shown in the drawings is formed of a plurality of roof sheets 1 extending continuously from one side of the car to the other, the adjacent side edges of neighboring sheets being flanged upwardly, as indicated at 2, and housed within outside carlines 3. Secured to the carlines adjacent the ridge of the roof are conventional running board saddles 4 of angle shape respectively having substantially vertical flanges 5 secured to the carlines and substantially horizontal flanges 6 to which the running board is connected.

The running board, generally designated by the reference numeral 7, comprises a plurality of longitudinally extending members 8 and a plurality of transversely extending bars 9. The outermost ones of the longitudinal members which form the sides of the running board are preferably of angle shape and respectively have substantially upright portions 10 which terminate in inwardly extending horizontal flanges 11, while the other longitudinal members which

are laterally spaced at suitable distances between the angle side members may advantageously be nothing more than upright plates or bars.

The upper edges of the longitudinal members are provided with a plurality of sets of aligned recesses 12 for receiving the transverse bars 9. The recesses are slightly inclined with respect to the vertical and, while those of each set are inclined in the same direction, alternate sets of recesses are preferably inclined in opposite directions.

After the bars 9 which are initially straight and free of any offset or bent portions are positioned in the recesses, the portions of the bars intervening between the longitudinal members are bent so as to be disposed in substantially upright positions, as indicated at 13. To prevent withdrawal of the bars from the recesses after being assembled with the longitudinal members, the depth of each of the recesses is greater than the width of the bars so that the metal defining or bounding the upper portions of the recesses may be bent downwardly over the upper edges of the bars. Not only are the bars thus firmly secured to the longitudinal members, but it will be seen that the portions 13 which are offset with respect to portions of the bars disposed within the recesses prevent the bars from shifting longitudinally and in this manner become disconnected from the longitudinal members.

The bottoms of each of the recesses 13 is located on the periphery of a circle which is tangent to the upper edges of the longitudinal members and whose diameter is substantially equal to the width of the bars 9 so that, when the portions 13 of the bars are bent into upright positions, their upper edges will be disposed in substantially the same plane as the upper edges of the longitudinal members. The running board is thus provided with a tread surface which is free of projections and is relatively smooth.

Projecting inwardly from the horizontal flanges 11 of the side angles of the running board and rigidly secured thereto in any suitable manner, as for example by welding, are a plurality of brackets 14 for respectively receiving bolts or the like 15 to rigidly connect the running board to the horizontal flanges 6 of the saddles 4. The running board is also preferably provided with additional brackets 16 for connecting it to the saddles adjacent the ridge of the roof, these brackets being in the form of plate members 55 which are connected, as by welding, to the two

longitudinal members disposed nearest the center line of the running board.

As it is more convenient to make the running board in a plurality of sections instead of as a single element capable of extending from one end of the car to the other, two saddles, as indicated in Figure 4, are employed at the adjoining edges of adjacent sections. In cases where the running board is secured to the car roof intermediate the ends of the sections thereof, a single saddle, such as is illustrated in Figure 5, is all that is required.

Where it is desirable, as in the case of refrigerator cars, to provide the running board with lateral extensions around a hatch opening 17 15 or the like, such extensions may be constructed in the same manner as the running board sections, differing therefrom only in size and shape. In Figure 1, the extension surrounding the hatch comprises two sections 18 and 19 respectively 20 having the same number of longitudinal members as the running board, another section 22 having four longitudinally extending members and another section 21 having only three such members. In each of these sections, the cross 25 bars are secured to the longitudinal members in precisely the same manner as the cross bars 9 are secured to the longitudinal members of the running board.

By reason of the method of assembly it is possible to use both for the longitudinal members 8 and the transverse members 9 stock having roughened edge surfaces so that when the parts are assembled the running board not only is provided with recesses, the edges of which form 30 anti-slip portions, but the upper surfaces of the bars and longitudinal members are also roughened so as to produce a running board which is practically slip-proof under all conditions.

From the foregoing, it will be perceived that a simple and rugged running board or walk way has been devised in which the component parts thereof are securely interlocked and accordingly will not work loose or come apart even under the most severe and adverse service conditions.

What I claim is:

1. The improvement in metal running boards for railway car roofs consisting of a series of 50 laterally spaced members adapted to extend longitudinally of the car roof, said members being respectively provided with substantially upright plate portions and the upper edges thereof having a plurality of inclined recesses, the recesses in each member respectively being in alignment with the recesses in the other members, the adjacent recesses in each of said members being oppositely inclined, and a plurality of transversely extending bars respectively disposed in said sets of aligned recesses, portions of said bars intervening between said members being disposed in substantially upright positions, the upper edges of said intervening portions being substantially coplanar with the upper edges of said longitudinal members to form tread surfaces and the width of the portions of the bars disposed in said recesses being less than the depth of the recesses so that the metal bounding the upper portions of the latter may be bent over the 70 upper edges of the bars to retain said bars in fixed position.

2. The improvement in metal running boards for railway car roofs consisting of a series of laterally spaced members adapted to extend longitudinally of the car roof, said members being respectively provided with substantially upright plate portions, the upper edges of said members having a plurality of sets of aligned inclined recesses, the adjacent sets of said recesses being oppositely inclined, and a transversely extending bar seated in each set of aligned recesses in said members, the upper ends of said recesses being bent over said bars, portions of the bars intervening between said plate portions being bent into substantially upright positions, each of said recesses having its bottom edge located on the circumference of a circle which is tangent to the plane passing through the upper edges of said plate portions and whose diameter is equal to the width of the bars so that after said portions of the bars are bent into upright positions the upper edges thereof will be disposed in the same plane as the upper edges of said plate portions to form tread surfaces.

3. The improvement in metal running boards for railway car roofs consisting of a series of laterally spaced members adapted to extend longitudinally of the car roof, said members being respectively provided with substantially upright plate portions and the outermost ones of said members being of angular shape in cross section, the upper edge of the plate portion of each of said members being provided with a plurality of sets of vertically inclined recesses, the recesses of each set being aligned with respect to like sets in the other of said members the recesses of adjacent sets being oppositely inclined, a plurality of transversely extending bars each respectively disposed in one of said sets of aligned recesses, portions of the bars intervening between said members being disposed in substantially upright positions, the upper edges of said portions being in the same plane as the upper edges of said members to form tread surfaces, and means rigid with each of said angularly shaped members for attaching the running board to the said roof.

4. The improvement in metal running boards for railway car roofs consisting of a pair of laterally spaced members angularly shaped in cross section adapted to extend longitudinally of the car roof, a plurality of platelike members interposed between said angularly shaped members extending substantially parallel therewith, the upper edges of all of said members being provided with a plurality of sets of aligned inclined recesses, the adjacent sets of said recesses being oppositely inclined, a plurality of bars extending transversely of all of said members and each respectively disposed in one of said sets of aligned recesses, portions of said bars extending between said members being substantially upright and the upper edges thereof being disposed in substantially the same plane as the upper edges of said members to form tread surfaces, means rigidly secured to the two intermediate plate members for connecting the central portion of the running board to said roof and brackets secured to said angularly shaped members, said brackets serving to connect the side portions of the running board to the said roof.

CHARLES S. JOHNSTON.
